[57] **CLAIM**

The ornamental design for a golf club head cover, as shown and described.

DESCRIPTION

FIG. 1 is a front elevational view of a golf club head cover showing my new design;

FIG. 2 is a right side elevational view thereof with the left side view being a mirror image thereof;

FIG. 3 is a rear elevational view thereof;

FIG. 4 is a top view thereof; and,

FIG. 5 is a bottom view thereof.

The broken line showing of a number on FIGS. 1 and 4 is for illustrative purposes only and forms no part of the claimed design. The broken line of FIGS. 3 and 5 show conventional stitching.
